UNITED STATES PATENT OFFICE.

DARWIN C. BOYCE, OF QUINNIMONT, WEST VIRGINIA.

CAR-LOADING APPARATUS.

SPECIFICATION forming part of Letters Patent No. 503,364, dated August 15, 1893.

Application filed April 8, 1893. Serial No. 469,499. (No model.)

To all whom it may concern:

Be it known that I, DARWIN C. BOYCE, a citizen of the United States, residing at Quin-
nimont, in the county of Fayette and State of
5 West Virginia, have invented a certain new
and useful Improvement in Car-Loading Apparatus, of which the following is a specifica-
tion.

My invention relates to the improvement of
10 mechanism for loading cars and the objects of
my invention are to provide a simple, reliable
and effective mechanism by means of which
box cars may be readily and uniformly loaded
with coal or other material; to so construct
15 and operate said mechanism as to provide for
the proper distribution of the coal within the
car to admit of the conveyer being supported
at various angles and to produce other im-
provements which will be more specifically
20 pointed out hereinafter. These objects I ac-
complish in the manner illustrated in the ac-
companying drawings, in which—

Figure 1 is a side elevation of my improved
25 coal loading apparatus showing for the sake
of clearness, one of the conveyer frame sides
partly broken away. Fig. 2 is a front elevation
of my improved loading apparatus shown
within a car. Fig. 3 is a plan view of the
30 operating engine and connected parts. Fig. 4 is
an enlarged detail view of the automatically
end loading chute and Fig. 5 is a detail view
in elevation of one of the adjustable prop
holders.

Similar numerals refer to similar parts
35 throughout the several views.

2 represents a conveyer frame which con-
sists essentially of two normally horizontal
parallel side beams 3 connected by a bottom
plate 4 the latter extending from the rear end
40 of the conveyer frame to a point in the for-
ward end portion thereof and a central par-
tition plate 5 which is supported between
said side beams at the center of their height
45 and which extends from the rear end portion
thereof to a point in the forward end portion
of said frame.

6 and 7 represent vertical frame standards
which are arranged on opposite sides of the
conveyer frame and 8 represents oppositely
50 located frame arms which extend rearwardly
from the rear frame posts 6 and has mounted
in bearings thereon a cross shaft 9 which ex-

tends beneath the rear end portion of the con-
veyer frame 2 and carries supporting wheels
10 upon which the rear end portion of the con- 55
veyer frame rests and is adapted to travel.

Supported from opposite sides of the for-
ward portion of the conveyer frame 2 are suit-
able reels or spools 11 which are adapted to
have secured thereto and wound thereon the 60
ends of supporting chains 12 which extending
upwardly pass over pulleys 13, said pulleys
being carried on the end portions of a trans-
verse shaft 14 each end of the latter being
journaled as shown in a traveling bracket 15. 65
Each of these brackets 15 is mounted on suit-
able track wheels 85 which rest and are adapt-
ed to travel upon the upper sides of horizon-
tal frame beams 86 which extend in the direc-
tion of the length of the conveyer beams 3. 70

Supported upon suitable hangers 16 which
depend from the under side of the frame 2 at
a point preferably in front of the center of
the length thereof is a suitable engine 17 of
which 18 represents the steam supply pipe. 75
This engine through its piston 19, connecting
rod 20 and crank shaft 21 rotates a gear wheel
22 on said shaft. Supported in suitable bear-
ings 23 in rear of said crank shaft is a shaft
24 which carries on one end a gear wheel 25, 80
which gears with the crank shaft wheel 22.
This shaft 21 also carries on its opposite end
a sprocket wheel 26 and upon its central por-
tion a gear wheel 27 the latter being keyed to
slide upon said shaft. This wheel 27 is loosely 85
embraced as shown in Fig. 3 of the drawings
by the bifurcated end of a lever 28, the latter
extending laterally outward and being pivot-
ally connected with a lever arm 29 one end
of which is pivoted at 30 to the bottom plate 90
31 of the engine supporting hangers.

To the outer side of one of the frame beams
3 is pivoted above the engine sprocket wheel
26 a double sprocket wheel 33 which is con- 95
nected with the wheel 26 by a chain 34.

Journalized in the forward end portions of
the conveyer frame side pieces 3 is a trans-
verse shaft 35, one of the outer projecting
ends of which carries a sprocket wheel 36
which is connected with a double sprocket 100
wheel 33 by a driving chain 37. The shaft
35 carries on the inner sides of the conveyer
frame side pieces, sprocket wheels 40 over
which run parallel conveyer chains 41, said

- conveyer chains extending parallel with and above and below the central partition plate 5 of the frame 2 and running over sprocket wheels 42 journaled in the rear end of said 5 conveyer frame. These conveyer chains carry as shown in the drawings, at desired intervals suitable transverse conveying flights 43, which are adapted when said chain is moved to travel adjacent to the partition plate 5.
- 10 Supported upon the engine supporting plate 31 beneath the wheel 27 is the forward end portion of a rearwardly extending rack bar 45, the rear end of the latter being pivotally connected with the framework 6.
- 15 47 represents a chute which is arranged above and at an angle from the rear portion of the conveyer frame and which may lead to a coal screen or tipple or other desirable feeding place.
- 20 Leading downwardly and upwardly from the open under side of the forward end portion of the conveyer frame are oppositely located fixed chutes 49, the latter being arranged on opposite sides of the center of the width 25 of said conveyer frame. To the lower and outer end portions of each of these chutes 49 are fulcrumed the upper and inner end portions of a chute section 50 to the remaining end of which is fulcrumed a chute section 51. To 30 the under side of each of these chute sections 51 and at the rear end thereof is affixed a plate 52 which projects past the rear end of said chute section and forms a support when said sections are open for the outer end of the 35 section 50.
- Extending vertically downward from the under side and forward end of each of the conveyer frame side pieces 3, is a frame bar 53.
- 40 54 represents socket pieces each of which consists as shown in the drawings of a central portion 55, which is mounted upon a pivot pin 56 which projects rearwardly from one of the frame bars 53. From this portion 55 there project two or more radial socket arms 57, the latter preferably being of different lengths and being formed with end sockets of different depths. Into one of the socket arms 57 of each of the socket pieces 54 is adapted to be inserted the inner end of an upper arm 59, 45 the outer end of the latter bearing against the cross plate 52 of the chute sections and thus being made to support said chute sections at the desired incline.
- 50 Fulcrumed to the under side of the conveyer frame at a point 60 in the forward half thereof is the rear end of a forwardly and downwardly inclined plate 61. The forward portion of this plate 61 beneath the open forward end portion of the conveyer frame serves 55 as a bottom plate for the inclined chute 62, the latter being formed by side plates 63 which rise from the sides of said plate 61. To the sides 63 of the chute 62 in the forward end portion of the latter are secured the lower ends of supporting chains 64. These chains extend upwardly above the chute and are connected with the inner and upper ends of out-

wardly and thence downwardly extending weight arms 65, the latter being fulcrumed at points 66 to a cross rod 67 which extends between the frame pieces 53. To this cross rod or bar 67 between the weight arms 65 is secured the upper end portion of a chute end plate 68, the latter depending from said bar and normally closing the front end portion of the chute 62 within which it projects. The weight arms 65 are as shown on the drawings provided on their lower ends at the greatest distance from their fulcrumed points with suitable weights 70, the latter serving to so support said weight arms as to result in the desired elevation of the chute 62. As illustrated in Fig. 2 of the drawings by the position of the right hand chute sections 50 and 51, it is evident that said chute sections may be compactly folded inward one upon the other against the framework of my apparatus by first removing the prop 59.

The method and means of utilizing my improved loading device are as follows: The forward end portion of the apparatus with which are connected the various chutes as described, is adapted when the side chutes are folded inward as above described to be inserted within the doorway 80 of an ordinary box car 81. This entrance of the conveyer and its chutes within said box car is effected by putting the engine 17 into operation and thereby causing through the gear wheels 22 and 25 a rotation of the shaft 21 and the wheel 27 thereon. This wheel 27 being in gear with the rack 45 it will readily be seen that a forward rotation of the shaft 21 may result in the conveyer frame with which the engine is connected being fed forward by the traveling action of the wheel 27 upon the rack 45. This forward movement of the conveyer frame results in its rear portion traveling upon the rollers or track wheels 10 and in the forward movement of the traveling brackets or carriages 85 upon the beams 86. The conveyer having thus been sufficiently fed forward, I may cause a disengagement of the rack 45 and its driving wheel 27 by an outward movement of the lever 29 which must result as will readily be seen in the sliding of the wheel 27 out of engagement with said rack bar. The engine being set in motion it is evident that the coal or other material which is distributed within the rear portion of the conveyer frame from the chute 47 will be carried by the conveying apparatus consisting in the usual manner of the chains 41 and cross piece 43 to the front end of the conveying frame where the material thus carried forward will be discharged partially within the fixed side chutes 49 and partially within the front chute 62. The folding side chutes having been previously unfolded to the position indicated at the left side of the apparatus in Fig. 2, it will be seen that such coal or other material as is directed from the chutes 49 must pass outward and downward through said side chutes, thus delivering the coal into

the car on opposite sides of the doorway. That portion of the coal which is distributed into the chute 62 will collect therein until sufficient weight is attained to overcome the weight of the arm 65, when said chute 62 will drop downward turning on its hinged rod 60 and result in the discharge of the coal through the forward end of the chute. This downward movement of said chute must result in the arms 65 being lifted to the position shown in dotted lines in Fig. 4 of the drawings. When the coal ceases to flow within the chute 62, it is evident that the weight of the arm 65 will result in their dropping to their normal positions and in the consequent elevation of the chute 62 and closing of its forward end by the plate 68. From this method of operation, it will readily be seen that coal from a screen or other point may convey directly to a box car and that the chutes will distribute the same therein in a substantially uniform manner.

By the use of my machine the ends of the car may be as completely and quickly loaded as the central portion thereof and by setting the chutes at varying angles which may be accomplished by inserting the prop 59 into different socket projections 57, the points of distribution may be changed.

30 By rotating the reels 11 and winding or unwinding the chains 12 thereon, it will be seen that the conveyer frame may be raised or lowered to different angles thus admitting of the adjustment of said conveyer frame to facilitate its use under varying circumstances.

It is evident that the conveying and discharging apparatus herein described may be employed for other purposes than those herein specified where it is desired to convey or 40 discharge coal or other material from one point to another.

It is evident that coal or other material might be discharged from the rear end of the conveyer frame into a suitable receptacle below by reversing the movement of the engine and thereby reversing the direction in which the conveyer chains are traveling.

From the construction which I have shown herein and described it is evident that a simple, convenient and reliable apparatus is provided which will greatly facilitate the loading of box cars and the distribution of the load therein.

Having now fully described my invention, 55 what I claim, and desire to secure by Letters Patent, is—

1. In a car loading apparatus the combina-

tion with a suitable framework, of a conveyer frame, an endless conveyer therein, rotary supports 10 on said framework upon the rear portion of which said conveyer frame is adapted to rest and run, traveling shaft carrying brackets or carriage 15 upon said framework above said conveyer frame, suitable pulleys 13 on said shaft, chains 12 passing over said pulleys and connected with reels on said conveyer frame and an engine 17 supported from said conveyer frame and means for driving said conveyer from said engine substantially as and for the purpose specified.

2. In a car loading apparatus the combination of the framework, a sliding conveyer frame supported thereby, an endless conveyer in said frame, an engine supported from said frame, a shaft 21 operated substantially as 75 described from said engine, a gear wheel 27 on said shaft and a rack bar 45 connected with said supporting framework, the teeth of said rack bar being in engagement with said wheel 27 substantially as and for the purpose 80 specified.

3. In a car loading apparatus the combination with a suitably supported sliding conveyer frame and an endless conveyer running therein, of fixed chutes 49 leading downward 85 and outward from the forward end of said conveyer frame, and jointed chute sections 50 and 51 jointedly connected with said fixed sections 49 and means for supporting said jointed sections at an incline from the conveyer substantially as and for the purpose 90 specified.

4. In a car loading apparatus the combination with a suitably supported sliding conveyer frame and an endless conveyer running 95 therein as described, of supported fixed chutes 49 leading outward and downward from the open forward end portion of the conveyer frame, jointed side chute sections jointedly connected with said chute 49 and communicating therewith, a chute 62 supported beneath said forward end of the conveyer and having its inner end pivoted to the frame of the latter, a permanent end gate 68 which normally closes the outer end of said chute 100 62 as described, pivoted weight arms 65 fulcrumed above said chute and supporting chains connecting the upper ends of said weight arms with said chute 62 substantially as and for the purpose specified.

DARWIN C. BOYCE.
